UNITED STATES PATENT OFFICE.

WILLIAM STANAT, OF CLEAR LAKE, WISCONSIN.

KNIFE-CYLINDER.

1,076,714.

Specification of Letters Patent. Patented Oct. 28, 1913.

Application filed January 13, 1913. Serial No. 741,873.

To all whom it may concern:

Be it known that I, WILLIAM STANAT, a citizen of the United States, resident of Clear Lake, Polk county, Wisconsin, have 5 invented certain new and useful Improvements in Knife-Cylinders, of which the following is a specification.

My invention relates to knife cylinders and particularly to those used for cutting 10 material such as ensilage.

The object of my invention is to provide a cylinder having knife seats therein which will allow the convenient adjustment of the 15 knives or the removal of a knife entirely from the cylinder without disturbing the other knives.

The invention consists generally in various constructions and combinations all as hereinafter described and particularly 20 pointed out in the claim.

In the accompanying drawings forming part of this specification, Figure 1 is a vertical sectional view through a knife cylinder and the feeding apparatus therefor, Fig. 2 25 is a plan view of the knife cylinder, Fig. 3 is a detail sectional view, showing the means for adjusting a knife in its seat and in the cylinder, Fig. 4 is a sectional view on the line $x-x$ of Figure 3.

30 In the drawing, 2 represents a suitable frame, 3 a carrier belt and 4-4 and 5-5 pairs of feed rolls between which the material is fed to the cylinder.

6 is a shaft, journaled in bearings in the 35 frame of the machine and driven from a suitable source of power. Upon the shaft 6 the heads of the cylinder are keyed. These heads consist preferably of a hub 7, a series of spokes 8, and rims 9, all cast in 40 one piece, and at suitable intervals the rims are provided with peripheral recesses 10. Between these recesses the rims are provided with tangentially arranged seats or 45 sockets 11, extending partially through the rims, preferably, and adapted to receive the ends of knife blades 12, which are diagonally mounted in the said sockets and provided with beveled cutting edges 13.

As shown in Fig. 2, the cutting edges of 50 the knives are at an angle to the axis of the cylinder. This is preferably effected by arranging the seats or sockets in the opposite heads in staggered relation to one another and fitting the ends of the blades in the 55 sockets to slide transversely therein, with their cutting edges arranged to make a sheer

cut as they sweep past a stationary knife 14 mounted in the frame of the machine. The knife blades are curved transversely to fit the curvature of the seats and conform 60 to the peripheries of the heads and follow the curvature of the outer faces of the rims in the adjustment of the knife blades with respect to the stationary plate. Each socket in the cylinder heads has an outer and an 65 inner bearing surface, the inner surface, due to the curvature of the head, being of greater area than the outer surface, and both surfaces present broad bearings for 70 the ends of the knife blades and coöperate with the securing means to prevent the blades from working loose in the operation of the cylinder.

Each knife blade is preferably locked on its seat by a set screw 14' having a jam nut 75 15, and mounted in the inner portion of the rim and engaging the inner face of the blade to clamp it securely in its seat. The engagement of the set screws with the knife blade forces the blade outwardly against the 80 outer wall of the socket which, as stated above, has a broad frictional surface to meet the surface of the blade and prevent it from slipping or working loose. Outward movement of the blades is effected by means 85 of adjusting screws 16 mounted in the walls of the rims at one end of the recesses 10 and secured by means of jam nuts 17. By loosening the screws 14' any one of the blades may be removed from the cylinder without 90 disturbing the other blades and by means of the screw 16 any blade can be adjusted at one or both ends, as desired. As the clamping screws do not enter the blades, but merely contact therewith, I am able to 95 adjust the blades edgewise and clamp them at any point within the range of their edge-wise adjustment. I am thus able to easily and quickly adjust the blades to compensate for wear of their cutting edges.

I have found that the broad bearing surfaces for the blades in the heads of the cylinder form a substantial backing or support for the blades and insure the locking of the blades by means of the clamping screws and 100 positively prevent their working loose in the operation of the cylinder.

I claim as my invention:

A knife cylinder provided with a head at each end thereof, each head having a series 110 of peripheral recesses at intervals therein, the walls of said heads between said recesses

having peripheral sockets extending tangentially therein and each provided with a rear wall forming the wall of the adjacent recess and inner and outer walls, knife blades extending from end to end of said cylinder and fitting edgewise within said sockets and braced and supported on both sides by the walls of said sockets, clamping screws mounted in one wall of said sockets and 10 contacting with said blades to clamp them against the opposite wall of said sockets, adjusting screws mounted in the rear walls of said sockets and accessible through said

recesses and engaging the rear edges of said blades for forward adjustment thereof, said 15 sockets having end walls to engage the ends of said blades and form guides therefor, said clamping screws being adapted to clamp said blades at any point within the range of their edgewise adjustment. 20

In witness whereof, I have hereunto set my hand this 8th day of January, 1913.

WILLIAM STANAT.
